UNITED STATES PATENT OFFICE.

GEORGE B. PICKOP, OF NEW BRITAIN, CONNECTICUT, ASSIGNOR TO P. & F. CORBIN, OF NEW BRITAIN, CONNECTICUT, A CORPORATION OF CONNECTICUT.

KNOB.

No. 874,621.

Specification of Letters Patent.

Patented Dec. 24, 1907.

Application filed July 26, 1907, Serial No. 385,659.

To all whom it may concern:

Be it known that I, GEORGE B. PICKOP, a citizen of the United States, residing at New Britain, county of Hartford, Connecticut, have invented certain new and useful Improvements in Knobs, of which the following is a full, clear, and exact description.

My invention relates to improvements in knobs, and particularly to an improved filling for the knob shank, by the use of which several advantages are attained, including a reduction in initial cost, less weight, greater uniformity of product, less liability of binding screw working loose, and greater speed in manufacture.

In the drawings Figure 1 is a longitudinal section of a portion of a knob and knob spindle, as the same appear in practice. Fig. 2 is a cross section of the filling piece, detached. Fig. 3 is a side elevation of the filling piece, looking from right to left. Fig. 4 is a cross section of the knob shank spindle and filling piece, assembled.

1 represents a portion of a knob.
2 is the knob shank, of conventional form.
3 is the binding screw which passes through the knob shank and takes into a screw-threaded passage in the knob spindle 4.

Because the shank of the knob is considerably larger than the spindle 4, it is necessary to have a filling piece. This filling piece not only reinforces the knob shank, but also acts as a bearing for the spindle. My improved filling piece is formed of a parallel sided strip 35 of wrought metal bent into the shape best seen in Fig. 2, the outside being circular, the inside being of a suitable contour to receive the end of the spindle 4, so as to prevent the independent turning of the spindle in the 40 knob.

5 represents the cylindrical outer wall of the filling and 6—6 represent the angular inner wall of the filling.

7 is a screw-passage through the outer 45 wall 5, while 8 is a screw-passage through one of the inner walls 6.

The knob shank filling may be inserted into the knob shank and snugly fits the same. When in place, a portion of the knob shank, indicated at 9, is spun or forced down into the opening 7 in the outer wall of the filling piece, securely anchoring the same, and also furnishing a countersunk seat for the head of the screw 3. Thus far, it will be seen that

knob shank fillings constructed as aforesaid 55 may be very rapidly produced with little cost and of very light yet very strong construction. In the preferable form of the filling piece its construction is such that it serves the purpose of a spring washer to prevent the jarring loose of the screw 3. This end is accomplished by leaving a slight space between the angle of the inner members 6 and the outer member 5 of the filling piece. This space is seen in Fig. 2. When the screw 65 is inserted, it draws against the outer side of the knob shank and against the spindle 4. As the screw is set up, the drag of the screw is in a direction to spring the adjacent side of the inner wall of the filling, so as to put a 70 yielding strain at all times upon the screw-thread, thereby frictionally retaining the screw against danger of displacement by reason of jarring. The position of the inner wall 6 of the knob shank when the knob 1 75 and screw 3 and spindle 4 are in place, is shown in the section view, Fig. 4, and on comparison with the position of the same part shown in Fig. 2, it will be observed how the inner wall is sprung by the dragging action of the screw.

The knob shank filling is preferably made in one piece or strip, but I do not desire to limit myself to this particular form. When made in one piece, the ends of the strip are 85 bent at a suitable angle, so that when the strip is rolled up into the form shown, these angles will form a space between them corresponding substantially to the cross section of the spindle which it is intended to employ, the extreme ends of the strip being located within the surrounding circular wall of the filling piece formed by bending it to a shape corresponding to and adapted to fit within the shank 2.

What I claim is:

1. A knob shank filling comprising a circular outer wall arranged to fit within the knob shank, and an angular yielding inner wall arranged to receive a spindle of angular 100 cross section, and spaces between the outer wall and inner wall of the filling, to provide clearance to permit said wall to yield.

2. A knob shank filling comprising a wrought metal strip bent to form an outer 105 wall of cylindrical form and an inner wall of angular form.

3. A knob shank filling comprising a cy-

- lindrical outer wall, and an angular inner wall, said walls being spaced apart but secured together at one point.
4. A knob shank filling comprising a cylindrical outer wall, an angular inner wall, and means for yieldingly supporting the angular inner wall relatively to the cylindrical outer wall.
5. In a knob, a hollow shank, a filling piece therein comprising an outer wall adapted to the knob shank, and an angular
- inner wall adapted to a knob spindle, and a screw-passage extending through the knob shank and both the inner and outer wall of the knob shank filling one of said walls adjacent to the screw passage in the knob shank being yielding.
